Primary Examiner—Martie Thompson
Attorney, Agent, or Firm—Dunlap & Coddng[57] **CLAIM**

The ornamental design for a flower pot cover, as shown and described.

DESCRIPTION

FIG. 1 is a perspective view of our new flower pot cover design;

FIG. 2 is a reduced side elevational view thereof;

FIG. 3 is a reduced top plan view thereof;

FIG. 4 is a reduced bottom plan view thereof;

FIG. 5 is a reduced side elevational view of the design of FIG. 1, the only difference being the size of the base;

FIG. 6 is a side elevational view of a third embodiment of our new design;

FIG. 7 is a side elevational view of a fourth embodiment of our new design;

FIG. 8 is a side elevational view of a fifth embodiment of our new design; and,

FIG. 9 is a side elevational view of a sixth embodiment of our new design.

UNITED STATES PATENT AND TRADEMARK OFFICE
CERTIFICATE OF CORRECTION

PATENT NO. : Des. 360,386
DATED : July 18, 1995
INVENTOR(S) : Weder et al.

It is certified that error appears in the above-identified patent and that said Letters Patent is hereby corrected as shown below:

On the title page, under item [57],
under the DESCRIPTION, lines 6-7, please
delete "FIG. 5 is a reduced side elevational view of the
design of FIG. 1, the only difference being the size of
the base;", and substitute therefor --FIG. 5 is a side
elevational view of a second embodiment of our new
design;--.

Signed and Sealed this
Seventeenth Day of October, 1995
